Primary Examiner — Marcs A Jackson(74) *Attorney, Agent, or Firm* — Nixon & Vanderhye P.C.(57) **CLAIM**

The ornamental design for a candle jar, as shown and described.

DESCRIPTION

FIG. 1 is a top view of the candle jar according to the present invention;

FIG. 2 is an underside view thereof;

FIG. 3 is a side view thereof, all other sides being identical;

FIG. 4 is a perspective view thereof; and,

FIG. 5 is a perspective environmental view thereof.

The broken lines in FIG. 5 depict environmental subject matter and form no part of the claimed design. The remaining broken lines in FIGS. 1, 2 and 4 depict portions of the article that form no part of the claimed design.
